52 Claims.

(Cl. 12—51)

This invention relates to shoe-shaping machines and, as herein illustrated, is embodied in a machine for shaping shoe-upper parts, it being particularly applicable to shaping the top margins of substantially completed shoes.

In the manufacture of shoes, it is frequently found that the withdrawal of the making last destroys the shape of the shoe, especially around the ankle opening. This is especially noticeable with pumps and the like, and gives to the shoe an unsightly and wrinkled appearance which lessens its saleability. Frequently, the ankle opening of the shoe gapes open unduly.

Accordingly, an important object of the invention is to provide an improved machine for shaping shoe-upper parts to restore to the shoe the intended shape which was imparted thereto by the last.

In carrying out this object, the machine herein illustrated embodies a shoe-supporting form which may readily be inserted in a shoe and later withdrawn without disturbing the shape which has been imparted to the shoe. Coacting with the form are pressers for engagement with the outside of the shoe to mold the shoe to the shape of the form. In accordance with a feature of the invention, the shoe-supporting form is mounted on a support for limited movement, both lengthwise of the shoe and laterally thereof, the latter arrangement insuring the application of a uniform pressure on the opposite sides of the shoe as the pressers are brought into engagement therewith.

The accessibility of the shoe-supporting form, enabling the shoe to be applied thereto and removed with ease, is increased, in accordance with another feature of the invention, by mounting the pressers for movement not only laterally toward and away from the shoe but also heightwise of the shoe and longitudinally thereof. In the illustrated construction, this is effected by means of pressers which are pivotally interconnected at the heel end and slidably mounted in a carrier movable longitudinally of the shoe. The sliding movement of the pressers in the carrier is heightwise of the shoe.

Still another feature of the invention resides in an improved mechanism for applying a force to move the pressers laterally against the shoe. This mechanism, as illustrated, comprises toggle-like struts resting at their outer ends against abutments and at their inner ends engaging the shoe pressers. Preliminary pressure is first applied by the operator and then power is applied to move the struts past dead center thereby to

increase the pressure and to retain the applied pressure for a desired interval. As illustrated, a plurality of molding mechanisms are mounted on a turret, rotatable step by step, to bring successive shoe forms to a loading position.

During this rotation of the turret, the machine is arranged, in accordance with other features of the invention, so that an operating device associated with each molding mechanism engages with a fixed cam to cause the application of pressure. As the turret approaches completion of its cycle, another fixed cam operates to relieve the applied pressure, breaking the toggle of the struts and releasing a holding latch.

For ease and safety of operation of the machine, a novel arrangement is provided of an operator-controlled treadle which, when depressed, applies the preliminary pressure and, when released, actuates a clutch to start the movement of the turret. The application of preliminary pressure is effected through a plunger located at the center of the turret. Danger to the operator's fingers is minimized by arranging the treadle so that the turret cannot be started to apply full pressure until after the pressers have been brought fully into engagement with the shoe by initial depression of the treadle. Provision is also made for preventing premature depression of the treadle while the turret is still rotating, thus avoiding a possible breakage of machine parts.

These and other features of the invention will be best understood from a consideration of the following description, taken in connection with the accompanying drawings, in which

Fig. 1 is an elevation of the machine but showing only a single shoe-shaping or molding mechanism;

Fig. 2 is a detail view of the clutch-operating mechanism, taken at right angles to and from the right of Fig. 1;

Fig. 3 is a front elevation of the cams by means of which full pressure is applied to the shoe;

Fig. 4 is a side elevation, on a larger scale, of the shoe-shaping mechanism shown in Fig. 1;

Fig. 5 is an angular view of the cams shown in Fig. 3;

Fig. 6 is a front elevation of the shoe-supporting form and the cooperating pressers;

Fig. 7 is a detail section on the line VII—VII of Fig. 4;

Fig. 8 is another section on the line VIII—VIII of Fig. 4;

Fig. 9 is a horizontal section taken on the line IX—IX of Fig. 4, and

Fig. 10 is a similar section, enlarged, on the line X-X of Fig. 4, but with a shoe on the form.

The machine is of the turret type and comprises a plurality of operating mechanisms in each of which there is a shoe-upper-supporting form 12 and cooperating molding members or pressers 14 and 16 supported indirectly on a bracket 18 carried by a rotatable table 20. Preferably, six such molding mechanisms are provided on the table 20, although, for simplicity of illustration, only one has been shown. Secured to the table is a worm wheel 22 by which the table is rotated by a cooperating worm 24 on a shaft 26 which receives power from a drive pulley 28 through a clutch mechanism 30. The arrangement is such that preliminary pressure is applied to the shoe upper by the pressers 14 and 16 which are moved forwardly, downwardly and then inwardly toward the side of a shoe under the impulse provided by an operator-controlled treadle 32 pivoted on a bracket attached to a hollow base pedestal 34 and which serves also, in a manner to be later described, to operate a clutch-controlled mechanism, shown in Fig. 2, to cause the table 20 to rotate for one-sixth of a revolution. During this rotation, pressure is applied automatically to the pressers 14 and 16, which pressure is maintained throughout the greater part of a revolution of the table and then is released as the particular shoe-supporting form 12 returns to starting or loading position. A suitable indexing mechanism, to be described, is provided to cause the turning of the table to be stopped after each sixth of a revolution.

Each of the shoe-supporting forms 12 is positioned vertically with its heel-receiving end upward and is intended to support a shoe, heel end up and sole outward toward the operator. It being desirable to narrow the ankle opening of the shoe, the form is wedge shaped, being narrower at its upper end (Fig. 6) than at its lower end. The form is also narrowed (Fig. 10) heightwise of a shoe on the form, i. e., in a direction extending substantially normal to the tread surface of the sole of the shoe. A shoe may be presented to the form with its heel end or counter portion higher than the upper end of the form, causing the lower end of the form to be inserted first into the ankle opening, after which the heel end of the shoe is dropped to bring it into engagement with the narrow upper end of the form. To facilitate the positioning of the shoe on the form, the latter is provided with a forwardly tapering, offset portion 40 (Fig. 4) having a protective plate 42 of fiber or the like so that when the form is heated, as by means of an electric cartridge unit 44, there will be no marking of the inside of the shoe. Heating the form facilitates the molding of the shoe and may be used to shrink and iron the lining. This wedge-shaped extension 40 permits the shoe to be moved toward the machine until the fiber plate 42 engages the inside of the bottom of the shoe, whereupon it will be found that the upper edges of the shoe lie substantially vertically along the form 12 ready for the action of the pressers 14 and 16. Each of the forms 12 has a fin 43 projecting rearwardly toward the center of the machine and terminating in a substantially cylindrical portion 48 (Fig. 10) which is received in a correspondingly shaped slot 50 (Fig. 9) extending vertically of the forward edge of the bracket 18. The side edges 52 of this slot are cut back to allow a limited lateral swinging movement of the form in the bracket slot. Downward yielding

movement of the form in the casting is provided, against the resistance of a spring 54 which is received in the bore 56 of the cylindrical portion 48 to rest against the upper end 58 (Fig. 4) of that bore and against an arm 60 attached to the bracket 18. Upward movement of the form with respect to the bracket by the spring 54 is limited by means of a rod 62 extending through the bore 56 and the arm 60, this rod being provided with a knurled head 64 and with a nut 66 at the top and lock nuts 68 below the bracket 60. The uppermost position of the form with respect to the bracket may be adjusted by holding the knurled head 64 of the rod and turning either the nut 66 or nuts 68.

The pressers 14 and 16 are shaped substantially complementally to the shoe-supporting form 12, being substantially flat at their upper ends near the heel end of the form and being concave lower down, as shown in Fig. 10. Preferably, they are provided with work-engaging surfaces of a yieldable nature and, as shown in Fig. 10, comprise each a layer of leather 70 which may be riveted to the pressers and a layer of rubber 72 held in place by a thin, flexible, leather cover 74 tightly wrapped around the assembly and held in position by a lacing 76 (Fig. 4). By these members, pressure is applied to a shoe S chiefly along the upper edges thereof and will impart the shape of the form 12 to the shoe, thereby to determine the shape of the ankle opening.

As has been previously noted, these pressers 14 and 16 are supported for movement forwardly (i. e., outwardly from the machine and heightwise of the shoe), and downwardly, i. e., lengthwise of the shoe, and also inwardly of the shoe after the shoe has been positioned on the form. To this end, there is provided (Fig. 4) a carrier 80 supported on the upper end of a plunger 82 vertically slidable in a bore provided in the bracket 18 and normally held in upward position by a compression spring 84. The pressers are pivotally interconnected and, for this purpose, the upper end of the presser 14 is provided with a flange 86 which is bolted to a flange 88 formed integrally with a horizontal rod 90 (Figs. 7 and 8) passing through the carrier 80. Surrounding this rod is a rotatable sleeve 92 on the forward end of which is a flange 94 to which is bolted a flange 96 (Fig. 6) at the top of the presser 16. This concentric rod and sleeve supporting the pressers are normally drawn rearwardly toward the center of the machine in the carrier 80 by means of springs 98. In order that the pressers 14 and 16 may normally be held away from the shoe-supporting form 12, the rod 90 has a screw pin 100 joined by a spring 102 to another pin 104 which is threaded in the sleeve 92. The pin 100 passes through a slot 106 in the sleeve 92. In order that the degree of swinging movement may not be unlimited and that the pressers may be held in substantially the desired relation to the form 12, the pins 100 and 104, which are attached indirectly to the pressers, are positioned in slots 108 and 110 (Figs. 4 and 7) in the carrier 80. Thus, any substantial swinging movement of the pressers bodily together in the same direction when they are in a raised, open position is prevented.

Provision is made, as has already been noted, for the application of a preliminary pressure by the members 14 and 16 to a shoe supported on the form 12 and, for this purpose, the plunger 82 is provided with a rearwardly extending pin 112 carrying a roller 114, the pin passing through

a slot in the bracket 18 in which this plunger is supported. This roller is adapted to be engaged on its upper surface by the forward end of a lever 116 which is pivoted on a stud 118 within a fixed bracket 120. This bracket 120 is clamped by bolts 122 on the upper end of a hollow rod 124 which projects upwardly through a bore in the table 20 and is carried by the base pedestal 34. The rear end of the lever 116 projects through a slot into the bore 126 within the rod 124 where it overlies the upper end of a plunger 128 slidably mounted in this bore and connected by a rod 130 to the end of the treadle 32 which projects inside the pedestal 34. This rear end of the lever 116 is biased toward the plunger 128 by a spring 129, the downward movement of the rear end of the lever being limited by a stop screw 131. When the treadle is depressed against the tension of a spring 132, the forward end of the lever 116 is depressed, moving the carrier 80 downwardly. During this movement, the pressers are moved forwardly by reason of the engagement of a roll 134 with a groove 136 in a cam 140 rotatable on a shoulder near the upper end of the rod 124. The shape of this cam groove 136 is such that the outward movement of the pressers is completed before they drop into contact with the shoe. The roll 134 is pivoted in a casting 142 having a stud loosely fitting a bore 144 (Fig. 7) at the rear end of the rod 90 so that it is free from swinging with the pressers. Rotation of the casting 142 with the rod 90 is prevented by a guide bar 146 attached to the upper side of the carrier 80 and received in a slot in the upper edge of the casting 142.

As the treadle is depressed, therefore, the pressers are moved forwardly and downwardly and this downward movement is accompanied by movement of the lower ends of the pressers toward each other by a mechanism shown best in Fig. 6. This movement of the pressers inwardly against the shoe is effected by pivoted struts 150 received in horizontal recesses 152 provided in the outer sides of the pressers and terminating at their upper edges in shoulder abutments 154. The struts are pivotally supported on abutments formed at the upper end of arms 156 secured to the bracket 18 and extending outwardly and upwardly to provide ample space around the lower end of the form 12. This gives greater freedom for manipulation of the shoe as it is applied to the form and in case the shoe is provided with straps, sufficient room is provided so that these straps will not be caught in other mechanism. Rounded faces 178 at the lower edge of the recesses 152 prevent the struts 150 from falling below the pressers 14 and 16.

Each of the struts is forked at its outer end and pivoted to an abutment 160 slidably received in a cup-shaped member 162 in a horizontal bore in the corresponding arm 156 and held in position therein by nuts 164 and 166 threaded on the external surface of the member 162. At the inner end of each of the cup-shaped members 162 are slots 168 receiving reduced portions of the support 160 so that the abutment cannot turn relatively to the cup-shaped member. On the abutment is a rod 170 surrounded by a compression spring 172, the resistance of which may be adjusted by means of a nut 174 threaded on the rod 170. Thus, the strut abutment 160 can yield outwardly against the action of this spring 172. In order to maintain the spring adjustment, a lock screw 176 is threaded in the outer end of the nut 174. By adjusting the nuts 164, 166,

the lateral position of the abutment for the strut 150 may be adjusted bodily without altering the compression of the spring 172.

When the pressers 14 and 16 are moved downwardly and forwardly as the plunger 82 is pushed down, the rounded upper ends of the struts 150 will track along the recesses on the external surfaces of the pressers and come into engagement with the shoulder abutments 154, the continued movement of which will move the struts downwardly about their pivots, and this, in view of the inclination of the struts, will serve to urge the pressers toward each other. The arrangement is such that when a shoe is on the form and the pressers 14 and 16 are lowered to effect a molding operation, the strut members 150 will be carried with the pressers through and slightly below the horizontal to form a toggle and will then serve to hold the pressers in lowered position and in firm engagement with the sides of the work, even though pressure is no longer applied to the roll 114 on the plunger 82. The degree and manner of application of the pressure exerted against the sides of the shoe may be adjusted by turning the nuts 164, 166 and 174.

Prior to this application of full pressure which will carry the struts 150 beyond their dead centers and so hold the pressers in shoe-engaging position, it is desirable to maintain the preliminary pressure which has been applied through the treadle, the plunger 128 and the lever 116. To this end, the plunger 82 is provided with a ratchet plate 180 (Fig. 4) extending through a slot in that portion of the bracket 18 which guides the plunger 82. This ratchet is provided with teeth which are engaged by a pawl 182, pivoted on the bracket and held normally in engaging position by means of a tension spring 184.

As has been already mentioned, provision is made for rotation of the table 20 to carry successive shoe supports from loading position around the table and back to loading position again, this being effected through the worm wheel 22 and the worm 24. As the illustrated work support leaves the loading position with the table rotating counterclockwise, when viewed from above, the roll 114 on the plunger 82 will pass under a cam 188 (Figs. 3 and 5) having an inclined operating surface 190 and which is adjustably secured to the side of the bracket 120. To this end, the bracket is provided with a vertical groove 192 (Figs. 4 and 5) and the cam is held in position by bolts 194 entering the threaded holes 196 in the bracket. The operative surface 190 of this fixed cam inclines downwardly to the right and as the table is turned, the plunger 82 will be depressed to a point such that the struts 150 are depressed below their horizontal positions before the roll 114 leaves the cam surface thereby insuring that the full molding pressure will be maintained throughout the remainder of the rotation of the table or until positively relieved. During this turning movement, the grooved cam 140 at the top of the rod 124 will be turned by engagement of the rolls 134 in said grooves and will be revolved about the axis of the table. When a rotation of the table is nearly completed, the cam roll 114 will engage the top inclined surface 200 of a cam member 202 which is adjustably secured to the bracket 120 in a manner similar to that in which the cam 188 is held. Just prior to the engagement of the roll with the cam surface 200, the tail 204 of the pawl 182 will engage an inclined

surface 206 (Fig. 4) on a cam plate 208 adjustably secured to the bracket 120, as by screws 210, thereby releasing said pawl and allowing the plunger 82 to be pushed upwardly by the cam surface 208 far enough to break the toggle effect of the struts 150. The spring 84 will then be effective to continue the upward movement of the presser carrier 80 and the pressers, released from the cam 140, will be drawn away from the shoe by the combined action of the cross spring 102 and the side springs 98. When the particular shoe support 12 reaches loading position, the tail 204 of the pawl 182 will ride down an inclined surface 212 ready for reengagement with the ratchet 180 and the roll 114 will be positioned in a gap between the two cams 188 and 200 ready for the action of the treadle-operated lever 116 after the treated shoe has been removed and another one put in its place.

It has already been explained that the table 20 is provided with six work supports and molding devices. It is desired, therefore, that the driving apparatus shall automatically move the table one-sixth of a revolution and bring it to a stop. This is done by a table-turning mechanism similar to that described in British Patent No. 343,151. To this end, the worm wheel 22 (Fig. 2) has on its under surface a cam groove 220 provided with six depressions in its inner vertical face corresponding to the six shoe supports. When the machine is stopped, a roll 222 attached to a slide 224 urged to the left by a spring 226 engages one of these depressions. When the machine is started, in a manner to be presently described, by clockwise movement of a trip lever 230 against the tension of a spring 232 and the consequent raising of the tail of this lever, the cam surface in the groove 220 will cause the slide 224 to be moved toward the right in Fig. 2, with the consequent raising of an arm 233 pivoted in a bracket 256 on the frame. This arm 233 has a screw 234 which is raised into a position to keep the tail of the trip lever 230 raised, even when the clutch treadle is released to allow the clutch to remain in engagement until the table has rotated a sixth of a revolution. This position of the trip lever 230 is maintained until the next depression in the groove 220 comes into position to receive the roll 222 as one of the work supports comes into position at the loading station, whereupon the slide 224 is moved to the left, the screw 234 lowered and the trip lever 230 permitted to rise to cause declutching, as will be described.

The clutch 30 may be of any desired type. It will be assumed here, however, to be arranged as illustrated in Letters Patent of the United States No. 1,124,620, granted January 12, 1915, on an application of A. E. Jerram, in which case a clutch member 236 will correspond to the "pendent lever 134" of that patent. The treadle 32 is utilized to actuate the clutch mechanism in addition to operating the plunger 128. For this purpose, a crank arm 240 is provided which is fixedly secured to the shaft 242 which rocks with the treadle. The arm 240 is connected by a link 244, arms 246, 248 fixed to a rock shaft 250 and an adjustable rod 252 to one end of a lever 254 pivoted on a fixed bracket 256. The clutch-tripping arrangement is seen in Fig. 2. The lever 254 has pivoted to it at its end opposite to that to which the rod 252 is attached, a latch 258 which has a shoulder or hook for operating the clutch trip lever 230. The arrangement is such that the hook on the latch 258 is normally located below the cooperating portion of the

clutch trip lever 230. On depression of the treadle 32, however, the latch 258 is moved upwardly to bring the hook on the latch above and over the end of the trip lever 230. When the operator relieves the pressure on the treadle, the spring 132 raises the treadle. The latch 258 is consequently moved downwardly and its hook carries the right-hand end (Fig. 2) of the lever 230 downwardly, thereby effecting tripping of the clutch, the latch 258 being freed from the lever 230 by movement of the pendent member 236 to the right as the clutch is actuated.

When the treadle 32 is depressed to cause the pressers 14, 16 to move forwardly and downwardly and then inwardly toward the shoe to apply preliminary pressure to work on the form 12, such preliminary pressure as is applied is maintained by the cooperation of the pawl 182 with the ratchet teeth on the plate 180. In the arrangement shown in the accompanying drawings, the rod 252 is of such length (or is adjusted to be of such length) that, when the treadle 32 is depressed, the hook of the latch 258 is not raised above the end of the lever 230 until the pressers have been lowered through such a distance that the ratchet plate 180 has reached a position in which its second tooth from the lower end can be engaged by the pawl 182. Thus, until the pressers 14, 16 have been lowered to this extent, release of the treadle will not cause tripping of the clutch. This provides a safeguard against the operator getting his or her fingers trapped between the pressers 14, 16 and the inside form 12 and injured by the power application of pressure. When the pressers 14, 16 have been lowered to the extent indicated (that is, to an extent at which the second tooth on the ratchet plate 180 can be engaged by the pawl 182) by depression of the treadle, these members will so closely embrace the work that there is not room between them and the work for the operator's fingers to be trapped therein. Conversely, should the operator's fingers be trapped as the pressers are lowered by the treadle 32, the operator will instinctively release the treadle well before it has been lowered enough to bring the parts into such a position that release of the treadle will cause tripping of the clutch and consequent application of the full pressure under power.

As another safeguard, the lever 116 has a roll-engaging portion consisting of a member 260 pivoted to the end portion of the lever. When the clutch has been tripped and the roll 114 of the molding mechanism which was at the loading station has been carried from underneath the lever 116, the latter is held by the spring 129 with its left-hand end (Figs. 1 and 3) in raised position. At this time, a small spring 262 holds the pivoted member 260 in such position that a tail 264 on the member 260 engages a step 266 on a fixed plate 268 carried by the bracket 120. Thus, in such position of the parts, it is not possible to turn the lever 116 by depressing the treadle 32. This prevents the operator from prematurely depressing and releasing the treadle to cause the next tripping of the clutch before the next molding mechanism has been carried right around to the loading station and its roll 114 brought underneath the lever 116. When the roll 114 is moving into this position, it is traveling upwardly along the inclined face 200 of the cam member 202. In so traveling, it engages the pivoted member 260 and moves it up (clockwise in Figs. 1 and 4) to disengage the tail 264 from the step 266. The lever 116 is then per-

mitted to be turned about its pivot on depression of the treadle 32. The arrangement described prevents the machine suffering damage through premature depression of the treadle, bringing the left-hand end portion of the lever 116 into the path of movement of one of the rolls 114 and being struck by the moving roll as the turret rotates. The pivoted member 260 is provided with an extension 270 which is accessible to the operator to release the tail 264 from the step 266 in the following circumstances which may sometimes, though infrequently, occur. If the operator on depressing the treadle 32 releases it at such a stage that the pawl 182 engages the first tooth (from the lower end) of the ratchet plate 180, the clutch will not be tripped but the roll 114 of the molding mechanism at the loading station will be held by the pawl depressed below and spaced from the member 260 which will have been raised by the lever 116 when the treadle was released and, consequently, the tail 264 will latch against the step 266, preventing the treadle being depressed and released once again to effect tripping of the clutch. In such case, the operator will manually release the member 260 by means of the extension 270 to allow the treadle 32 to be operated.

In using the machine, the operator will remove the treated shoe from the form 12 at the loading station and replace it with another shoe which he will push against the form until the inside of the heel seat portion of the shoe engages the fiber plate 42 and the heel end or counter portion of the shoe rests snugly against the heel end of the form. Then, he will depress the treadle 32, thus raising the plunger 128 and causing depression of the plunger 82 and the carrier 80 mounted thereon. By this movement, the pressers will be moved forwardly or toward the bottom and, hence, height-wise of the shoe and downwardly or longitudinally of the shoe by the action of the grooved cam 140. When the downward movement is partly completed, the struts 150 will be engaged by the shoulder abutments on the pressers and pushed downwardly toward a horizontal position thus forcing the pressers inwardly against the sides of the shoe. As this occurs, the form may yield vertically, if necessary, and the pressure will be equalized by the provision for limited lateral movement of the form. Whatever pressure is applied will be retained by the action of the latch 182. Thereupon, as the treadle is released, the clutch will be actuated in a manner already described and the turret given one-sixth of a revolution, thereby carrying the roll on the plunger 82 beneath the cam surface 190, thus still further depressing the carrier 80 and forcing the struts past dead center so that they act as a toggle and hold the pressers in engagement with the shoe. This continues until the turret rotates far enough so that the toggle is broken by the action of the cam surface 200, the pawl 182 being also released by the cam 206, thereby allowing the spring 84 to force up the plunger on which the carrier 80 is mounted. The pressers will then be drawn laterally away from the shoe, vertically above the shoe and then back, heightwise of the shoe, leaving the latter free for removal from the form.

Having described my invention, what I claim as new and desire to secure by Letters Patent of the United States is:

1. In a shoe-shaping machine, a shoe-supporting form supported for limited lateral movement, pressers movable into engagement with the sides

5 of a shoe supported on the form, abutments spaced from said pressers, struts interconnecting the abutments and the pressers, and means for causing said struts to be moved to pressure-applying position, the pressure against the sides of the shoe being equalized by lateral movement of the form.

10 2. In a shoe-shaping machine, a shoe-supporting form supported for yielding movement longitudinally of the shoe and mounted for movement laterally of the shoe, pressers engageable with the sides of a shoe on the form, and means for moving said pressers longitudinally of the shoe and inwardly toward the shoe.

15 3. In a shoe-shaping machine, a shoe-supporting form positioned heel end up and mounted for downward yielding movement, said form tapering outwardly toward the forepart of a shoe on the form, and interconnected pressers movable longitudinally of the shoe to engage the sides thereof, the form yielding when the pressure applied is excessive.

20 4. In a shoe-shaping machine, a shoe-supporting form mounted for movement longitudinally of the shoe, yieldable means resisting said movement, means for limiting the movement of the form in the direction of an end of the shoe, pressers engageable with the sides of a shoe on the form, and means for moving said pressers in opposition to said yieldable means.

25 5. In a shoe-shaping machine, a shoe-supporting form positioned with its longitudinal axis vertical and its heel end up, means for yieldably urging said form upwardly, means for adjustably determining the limit of upward movement of the form, and pressers movable into engagement with the end and sides of a shoe on the form.

30 6. In a shoe-shaping machine, a shoe-supporting form narrowed heightwise toward the foot opening of a shoe on the form, and pressers movable heightwise of the shoe and hence substantially normally to the tread surface of the shoe sole and then in a direction toward the shoe to bring them against the sides of the shoe thus supported.

35 7. In a shoe-shaping machine, a shoe-supporting form adapted to be received in the heel end of the shoe and narrowed heightwise of the shoe toward the shoe opening, coacting pressers adapted to be brought against the sides of a shoe on the form, and means for moving said pressers heightwise of the shoe and then longitudinally of the shoe to bring them into engagement therewith.

40 8. In a shoe-shaping machine, a shoe-supporting form adapted to be received in the heel end of the shoe and narrowed heightwise of the shoe toward the shoe opening, coacting pressers adapted to be brought against the sides of a shoe on the form, and means for moving said pressers heightwise and longitudinally of the shoe into engagement therewith and for forcing the pressers laterally against the sides of the shoe.

45 9. In a shoe-shaping machine, a shoe-supporting form adapted to hold a shoe in depending position with the top edges of the shoe in a substantially vertical plane, said form being provided with an offset portion at its heel end against which the heel seat of the shoe may be brought to insure said position of the shoe, and pressers mounted for movement longitudinally of the form and laterally toward the form, said offset portion being farther from the pressers at its heel end.

50 10. In a shoe-shaping machine, a shoe-sup-

porting form, pressers movable into engagement with a shoe on the form, means for supporting said pressers for movement longitudinally of said form, and means for supporting the form to yield in the direction of movement of the pressers.

11. In a shoe-shaping machine, a shoe-supporting form, pressers movable into engagement with opposite sides of a shoe supported on the form, and a movable carrier, said pressers being pivotally supported on the carrier and movable with respect to the carrier in the direction of the axis of their pivots.

12. In a shoe-shaping machine, a shoe-supporting form, a carrier movable longitudinally of a shoe mounted on the form, pressers engageable with opposite sides of a shoe on the form, said pressers being mounted on said carrier for movement toward and away from the sides of a shoe and for movement heightwise of the shoe, means for moving the carrier, and means for effecting said heightwise and lateral movement of the pressers to bring them into engagement with the shoe.

13. In a shoe-shaping machine, a shoe-supporting form, a carrier movable longitudinally of a shoe mounted on the form, pressers engageable with opposite sides of a shoe on the form, said pressers being mounted on said carrier for movement toward and away from the sides of a shoe and for movement heightwise of the shoe, means for moving the carrier, means for effecting said heightwise and lateral movement of the pressers to bring them into engagement with the shoe, and means for automatically returning said pressers to inoperative position when the carrier is retracted.

14. In a shoe-shaping machine, a form for supporting the upper edge of a completed shoe, pressers adapted for engagement with the outside of the shoe along said top edge, a carrier movable longitudinally of the shoe, said pressers being movably mounted on the carrier, means for moving the carrier longitudinally of the shoe, and means for transforming said longitudinal movement to a movement of the pressers heightwise of the shoe and laterally toward and away from the shoe.

15. In a shoe-shaping machine, a shoe-supporting form, a movable carrier, pressers movably supported on said carrier, means for producing movement of the carrier in one direction, and means for automatically moving the pressers heightwise of the shoe to cause them to engage the shoe.

16. In a shoe-shaping machine, a shoe-supporting form, a carrier movable in a direction parallel to a major axis of the form, pressers on said carrier, means for moving said carrier to cause the pressers to approach a shoe on the form, and cam means operated by sidewise movement of the shoe and form for causing movement of the pressers in a direction angularly related to the direction of movement of the carrier.

17. In a shoe-shaping machine, a shoe-supporting form, a movable carrier, pressers movably supported on said carrier, means for producing movement of the carrier in one direction, and means for automatically moving said pressers in two angularly related directions which are different from the direction of movement of the carrier as the carrier is moved.

18. In a shoe-shaping machine, a shoe-supporting form engageable with the heel end of the shoe end adapted to support a shoe with the

toe end in depending position, a carrier movable vertically, pressers pivoted about a common axis in said carrier, means for moving the carrier, and means for automatically moving the pressers horizontally along said axis to engage the sides of a shoe.

19. In a shoe-shaping machine, a shoe-supporting form engageable with the heel end of the shoe and adapted to support a shoe with the toe end in depending position, a carrier movable vertically, pressers pivoted about a common axis in said carrier, means for moving the carrier, and means for automatically moving the pressers horizontally in a direction oblique to said common pivotal axis to engage the sides of a shoe.

20. In a shoe-shaping machine, a shoe-supporting form, a movable carrier, pressers adapted for engagement with a shoe on the form and movably mounted on said carrier, and fixed means loosely connected with said pressers operative on movement of the carrier to move said pressers toward the shoe.

21. In a shoe-shaping machine, a shoe-supporting form, a movable carrier, pressers adapted for engagement with a shoe on the form and movably mounted on said carrier, and a toggle means rendered operative by movement of the carrier to force said pressers against the sides of a shoe on the form.

22. In a shoe-shaping machine, a shoe-supporting form, a movable carrier, pressers supported in said carrier for movement heightwise of a shoe on the form, and springs between said carrier and said pressers opposing said heightwise movement.

23. In a shoe-shaping machine, a frame, a shoe-supporting form mounted thereon, a carrier movable independently of the form toward and away from said form, pressers adapted to coact with a shoe on the form, said pressers being mounted on the carrier for swinging movement toward and away from the sides of the shoe, and means attached to the pressers and engaging the carrier for positively limiting swinging movement of the pressers toward each other.

24. In a shoe-shaping machine, a shoe-supporting form, a movable carrier, pivotally interconnected pressers adapted to be moved against a shoe on the form, said pressers being mounted on the carrier for movement heightwise of the shoe, means for moving the carrier to bring the pressers into engagement with the shoe, and spring means for swinging said pressers apart and for moving them heightwise of the shoe.

25. In a shoe-shaping machine, a shoe-supporting form, pressers movable laterally to engage the sides of a shoe on the form and movable in another direction, abutments on opposite sides of said form and spaced therefrom, and toggle-like struts between said pressers and said abutments and out of alignment when the pressers are away from the shoe, movement of the pressers in said other direction being effective to straighten said toggle struts and force the pressers against the shoe.

26. In a shoe-shaping machine, a shoe-supporting form, pressers engageable with a shoe on the form, abutments spaced from the form, struts extending between the abutments and the pressers, and a yielding support for the abutments.

27. In a shoe-shaping machine, a shoe-supporting form, pressers engageable with a shoe on the form, abutments spaced from the form, struts extending between the abutments and the pressers.

ers, and means for adjusting the position of said abutments.

28. In a shoe-shaping machine, a shoe-supporting form, pressers engageable with a shoe on the form, abutments spaced from the form, pivoted struts extending between the abutments and the pressers, supporting means for the abutments including springs, and means for adjusting the position of said supporting means without changing the tension of the springs.

29. In a shoe-shaping machine, a shoe-supporting form, coacting pressers, pivoted struts for moving said pressers toward the form, abutments for said struts, springs supporting said abutments, and means for adjusting the resistance of said springs.

30. In a shoe-shaping machine, a shoe-supporting form extending longitudinally of the shoe and adapted to be engaged at the heel end of the shoe, pressers movable toward and away from the sides of the shoe, abutment arms curved longitudinally of the shoe and laterally of the shoe to facilitate access to the form, and struts extending between said abutment arms and said pressers for forcing the pressers against the sides of the shoe.

31. In a shoe-shaping machine, a shoe-supporting form positioned heel end up, pressers movable toward and away from the sides of a shoe on the form, a support for said form, abutment-carrying arms extending outwardly and upwardly from said support to facilitate access to the form, and struts extending between said abutment arms and said pressers for forcing the pressers against the sides of the shoe.

32. In a shoe-shaping machine, a shoe-supporting form, a pair of presser members movable lengthwise of the form and toward and away from the form, a pair of abutment members spaced from the outer faces of said presser members, and struts pivotally connected to one pair of members, the other pair of members being provided with recesses receiving the ends of the struts and terminating in shoulder abutments against which the struts can press to force the presser members against a shoe on the form.

33. In a shoe-shaping machine, a shoe-supporting form, a pair of presser members movable lengthwise of the form and toward and away from the form, a pair of abutment members spaced from the outer faces of said presser members, and struts pivotally connected to one pair of members, the other pair of members being provided with recesses receiving the ends of the struts and terminating in shoulder abutments against which the struts can press to force the presser members against a shoe on the form, said recesses being extended in a direction substantially parallel to the longitudinal axis of the form thereby to permit a lengthwise movement of the presser members before the struts become effective to force them against a shoe on the form.

34. In a shoe-shaping machine, a shoe-supporting form, a presser member movable heightwise of a shoe on the form into engagement with said shoe, an abutment spaced from said presser member, and a connecting member interposed between said presser and the abutment for forcing the presser against the shoe, said connecting member having a capacity for ineffective movement with respect to one of the parts with which it is engaged in a direction heightwise of a shoe thereby to permit said heightwise movement of the presser.

35. In a shoe-shaping machine, a shoe-supporting form, a presser movable heightwise of a

shoe on the form into engagement with said shoe, an abutment spaced from said presser, and a strut interposed between the presser and the abutment and slidable with respect to one of the parts with which it is engaged in a direction heightwise of the shoe thereby to permit said heightwise movement of the presser.

36. In a shoe-shaping machine, a form adapted to be received in and to support a shoe, pressers movable toward and away from the sides of a shoe on said form and provided with shoulders, abutments spaced from the sides of the form, struts extending between said pressers and said spaced abutments in an inclined relation to an axis of the shoe, and means for moving said pressers along said axis to cause the shoulders on the pressers to engage the struts whereby the pressers will be forced inwardly against the shoe by movement of the struts toward a position normal to said axis.

37. In a shoe-shaping machine, a shoe-supporting form, pressers movable toward and away from the sides of a shoe supported on said form, fixed abutments spaced from said pressers, pivoted struts extending between said abutments and said pressers, and means for moving said pressers in a direction to cause said struts to force the pressers toward the shoe.

38. In a shoe-shaping machine, a shoe-supporting form, pressers movable toward and away from the sides of a shoe supported on said form, abutments spaced from said pressers, pivoted struts extending between said abutments and said pressers, means for moving said pressers in a direction to cause said struts to force the pressers toward the shoe, and ratchet means for retaining said pressers in engagement with the shoe.

39. In a shoe-shaping machine, a shoe-supporting form, pressers movable toward and away from the sides of a shoe supported on the form, pivotally supported toggle struts engaging said pressers, and means for moving said pressers longitudinally of the shoe beyond a position in which the toggle is straightened thereby to hold the pressers in engaged position.

40. A shoe-shaping machine of the turret type having a shoe-supporting form and coacting pressers rotatable around an axis, a cam operable on rotation of the turret to force said pressers into engagement with the shoe, and another cam operable on further rotation of the turret to relieve said engagement.

41. A shoe-shaping machine of the turret type having a shoe-supporting form and coacting pressers rotatable around an axis to bring said form into loading position, toggle-like struts movable past dead center to force the pressers against a shoe on the form and hold them there, a cam operable upon rotation of the turret for moving said struts and pressers into holding position, and another cam operable on further rotation of the turret for breaking said toggle.

42. A shoe-shaping machine of the turret type having a shoe-supporting form and coacting pressers rotatable about an axis to bring the form into operative position, a movable carrier for said pressers, a latch for holding said carrier when moved to pressure-applying position, a cam operable on rotation of the turret to move the carrier and force said pressers into engagement with a shoe on said form, and another cam operable on further rotation of the turret to release said latch.

43. In a shoe-shaping machine, a shoe-supporting form, a carrier movable heightwise of a

shoe on the form and longitudinally of the shoe form, pressers movably supported on said carrier and engageable with the sides of a shoe supported on the form, operator-controlled means for effecting successive initial movements of said carrier in two directions normal to one another to bring the pressers against the shoe, and power-operated means for continuing movement of the carrier in one direction thereby to move the pressers more firmly against the shoe.

44. A shoe-shaping machine of the turret type having a shoe-supporting form and coacting pressers on a turret rotatable around an axis to bring the form into loading position, and operator-controlled means located at and movable along said axis to impart an initial movement to the pressers to bring them against a shoe on the form.

45. In a shoe-shaping machine, a shoe-supporting form, pressers movable into engagement with a shoe on the form, treadle-operated means for moving the pressers into engagement with the shoe, and power-operated means associated with said pressers to operate them and comprising a clutch, said treadle being arranged to operate said clutch only after it has applied preliminary pressure, thereby to cause the power means to apply full pressure.

46. A shoe-shaping machine of the turret type having a shoe-supporting form and coacting pressers rotatable about an axis to bring the form into loading position, operator-controlled treadle means for applying a preliminary pressure to said pressers, and power means for applying additional pressure and including a clutch, said treadle means also having a connection to said clutch to operate it by a reverse movement after preliminary pressure has been applied by the operator.

47. In a shoe-shaping machine, a shoe-supporting form, a presser to engage a shoe on the form, manually-operable means to apply preliminary pressure to said presser, power means to apply additional pressure, and a treadle operable in one direction to actuate said manually-operable means and movable in the opposite direction to set in motion said power means.

48. In a shoe-shaping machine, a shoe-supporting form, a presser movable to engage a shoe on the form, means including an operator-controlled device for moving said presser against a shoe on the form, and power means for applying additional pressure to said presser, said operator-controlled means being constructed and arranged for initial movement in one direction to apply

initial pressure and for further movement in another direction to control the application of power.

49. In a shoe-shaping machine, a shoe-supporting form, a presser movable to engage a shoe on the form, means including a treadle for moving said presser against a shoe, and power means for applying additional pressure and including a clutch, said treadle being constructed and arranged for movement in one direction to apply initial pressure and for movement in the other direction to control said clutch.

50. In a shoe-shaping machine, a shoe-supporting form, a presser movable to engage a shoe on the form, operator-controlled means for moving said presser against a shoe on the form, power means for applying additional pressure and including a clutch, a treadle, a spring for turning said treadle, a connection between said treadle and said operator-controlled means, a movably mounted shouldered member for operating said clutch, and a connection between said treadle and said shouldered member, said connection being constructed and arranged to bring the presser into full engagement with a shoe before the shouldered member is moved far enough to engage over a clutch part thereby preventing premature application of power to said presser.

51. A shoe-shaping machine of the turret type having a plurality of shoe-supporting forms and coacting pressers on the turret rotatable about an axis to bring successive forms into loading position, a movable member positioned for cooperation with a presser at loading position to move it, and a latch for inhibiting the movement of said movable member after the presser has been rotated from loading position, said latch being released by the passage to loading position of the next succeeding presser and form.

52. A shoe-shaping machine of the turret type having a plurality of shoe-supporting forms and coacting pressers on a turret rotatable about an axis to bring successive forms into loading position, a presser-actuating member associated with each form, a lever at a fixed position and constructed and arranged to cooperate with said actuating member when the turret is at rest, operator-controlled means for moving said lever, a latch for preventing movement of said lever after the rotation of the turret has separated the lever and the actuating member, and means, operable by movement into coacting relation with the lever of the next succeeding presser-operating means, for releasing said latch.

GEORGE HAZELTON.
